[57] CLAIM

The ornamental design for a scale meter, as shown and described.

DESCRIPTION

FIG. 1 is an isometric view of the scale meter showing our new design;

FIG. 2 is a front elevational view thereof;

FIG. 3 is a side elevational view thereof, the other side being identical thereto;

FIG. 4 is a rear elevational view thereof;

FIG. 5 is a top plan view thereof;

FIG. 6 is a bottom view thereof; and,

FIG. 7 is a front elevational view showing an alternative to FIG. 2.

All views not shown being identical to those shown in FIGS. 3-6.
